Application filed May 2, 1927. Serial No. 21,814. Term of patent 14 years.

To all whom it may concern:

Be it known that I, GRACE TANCILL, a citizen of the United States, and a resident of the city of St. Louis, in the State of Missouri, have invented a new, original, and ornamental Design for a Dress, of which the following is a specification, reference being had to the accompanying drawing, forming part thereof.

Fig. 1 is a front perspective view of a dress showing my new design;

Fig. 2 is a back perspective view of the dress shown in Fig. 1.

The dress is distinguished by the arrange-

ment of parallel rows of ornamental shell stitching longitudinally disposed at the front and center of the dress and extending around the neck thereof; by parallel rows of shell stitching transversely disposed around the hip portion of the garment; and by transversely disposed rows of shell stitching adjacent the margin of the sleeves to simulate cuffs.

I claim:

The ornamental design for a dress, substantially as shown and described.

GRACE TANCILL.
